(57) **CLAIM**

The ornamental design for a paintball storage belt, as shown and described.

DESCRIPTION

FIG. 1 is a perspective view of a paintball storage belt, showing my new design;

FIG. 2 is a top plan view, thereof, the bottom plan view being a mirror image, thereof;

FIG. 3 is a front elevational view of the container holder portion, with the belt removed;

FIG. 4 is a left side elevational view thereof;

FIG. 5 is a right side elevational view thereof;

FIG. 6 is a rear elevational view thereof;

FIG. 7 is an exploded perspective view, the broken line showing of environment in the drawings being for illustrative purposes only and forming no part of the claimed design;

FIG. 8 is a perspective view, shown on a reduced scale, the broken line environment being for illustrative purposes only and forming no part of the claimed design;

FIG. 9 is a view of the inner side of the container holder portion; and,

FIG. 10 is a view of the outer side of the contain holder portion.
